UNITED STATES PATENT OFFICE.

CHARLES DUNNING, OF NEW ORLEANS, LOUISIANA, ASSIGNEE OF ONE-THIRD TO
GOTTLIEB SOLLBERGER, OF NEW ORLEANS, LOUISIANA.

DUMPING-CAR.

1,180,382.

Specification of Letters Patent. Patented Apr. 25, 1916.

Application filed September 20, 1915. Serial No. 51,655.

To all whom it may concern:

Be it known that I, CHARLES DUNNING, a citizen of the United States, residing at New Orleans, in the parish of Orleans and State 5 of Louisiana, have invented certain new and useful Improvements in Dumping-Cars, of which the following is a specification, reference being had to the accompanying drawings.

10 This invention relates to railway cars, and particularly to dumping cars.

The primary object of this invention is the provision of a very easily operated, simply constructed dumping car, wherein the 15 dumping operation may be effected by air operated means controlled from the engine of the train or may be effected in other ways by the application of power thereto.

A further object of the invention is the 20 provision of a dumping car having sides which, when unlocked, will yield outwardly for the discharge of material, and a floor formed in lateral sections, together with means whereby the floor sections may be 25 raised at the middle so as to discharge material laterally on both sides of the car beneath the sides of the car.

A further object of the invention is to provide simple but effective means whereby the 30 sides of a car may be held from any opening movement, these means being adapted to be shifted by hand into a released position and supported in this position.

A further object of the invention is to provide means whereby the operating means of 35 all the cars of a train may be connected to each other and operated from the engine of a train to secure a simultaneous discharge of material from all of the cars.

40 A further object of the invention is to so construct the car that it may be used either as a dumping car or as a flat car.

Other objects will appear in the course of 45 the following description.

My invention is illustrated in the accompanying drawings, wherein:

Figure 1 is a side elevation of a car constructed in accordance with my invention, the figure showing in dotted lines the position taken by one of the car stakes when the 50 side walls of the car are released; Fig. 2 is a top plan view of the car shown in Fig. 1; Fig. 3 is a section on the line 3—3 of Fig. 1 but with the car floor in its lowered position 55 and the sides of the car in their locked and

vertical position; Fig. 4 is a like view to Fig. 3 but showing the position taken by the car when the car is dumping and also showing the position taken by the sides at this time; Fig. 5 is a longitudinal fragmentary 60 section to the car shown in Figs. 1 and 2.

Referring to these drawings, 2 designates the framework forming the body of the car. This may be constructed in any suitable manner and is supported upon the trucks 3. 65 I do not wish to limit myself to any particular manner of constructing the framework upon which the car body is supported. As illustrated, this framework consists of transverse members 4 and longitudinal 70 members or sills 5 and 6. Disposed at the ends of the car are the vertical posts 7 with the end boards or pieces 8 hinged at 9 to a supporting base 10 so that these end boards or pieces 8 may be turned inwardly and 75 downwardly as will be later stated. Carried upon these posts 7 and extending longitudinally along the car are the rods 11. These rods support the swinging sides 12. These sides may be made in sections but preferably 80 each side extends the full length of the car. The side members 12 are shown as supported upon the rods 11 by means of straps 13.

Each side piece 12 carries upon it a plurality of stakes 14 whereby the side may 85 be locked in a vertical position. Each stake is longitudinally slotted as at 15 and a headed pin 16 is disposed in the side piece 12 to project therefrom and passes through the slot 15. The lower end of each stake is 90 reduced in cross sectional area as at 14^a and is adapted to be inserted beneath a strap 17 attached to the beam or sill 6. Disposed adjacent the lower edge of the side piece 12 is an L-shaped strap 18 forming a socket or 95 seat, open on one side, and disposed adjacent the upper edge of the piece 12 is an L-shaped strap 19, which, however, has its open end directed opposite to the direction of the open end of the strap 18. From this 100 construction it is obvious, as shown in Fig. 1, that a stake 14 may be raised out of engagement with the straps 17 and that when fully raised out of this engagement it may be rotated to the position shown in dotted 105 lines in Fig. 1, the upper end of the stake being received in a seat formed by an L-shaped strap 20 which is attached to the side wall 12. As many of these stakes 14 may be 110 used as is required to support the side walls 11

12 against the pressure of the material carried within the car. When the stakes are forced downward into engagement with the straps 17, it will be obvious that the side walls of the car will be held firmly in vertical position against any thrust from the load carried upon the car.

As illustrated most clearly in Figs. 3 and 4, the bottom of the car is formed in two sections designated respectively, 21 and 22. Both of these sections are alike. Each section of the floor is mounted upon a supporting rod 23 which extends longitudinally of the car and is supported in any suitable manner in the posts 7 or upon the beams 6. Disposed beneath the floor sections 21 and 22 and normally extending horizontally in parallel relation to these floor sections are the floor lifters designated 24. These are approximately triangular in form, as seen most clearly in Fig. 4, and each has outwardly projecting trunnions 25 which extend out through ball bearings 26 carried in the beams 6, these bearings being protected by cover plates 27 which are attached to the beams 6 in any suitable manner. The lifters 24 are therefore rotatable from a horizontal position to a vertical position, and vice versa. Each of the lifters along each forward edge is cut away as at 28 and mounted in this cut-away margin is a roller 29 which is adapted to rotatably engage with the under face of the corresponding floor sections 21 and 22. It will now be obvious that when these lifters 24 are raised from a horizontal to a vertical position, as shown in Fig. 4, they will lift up upon the floor sections 21 and 22 and these floor sections will be raised to the position shown in Fig. 4 which will cause the material on that floor section to be dumped laterally. The weight of the material tending to slide off the floor sections will force the sides 12 open, swinging them outward upon the pivot rods 11 and the material contained within the car will be discharged.

For the purpose of raising and lowering the lifters 24, I connect the lifters in one car to each other by means of chains or other flexible connections 30 so that all of the lifters will operate together. I dispose beneath the car in any suitable position the air cylinder 31 having therein a piston 32 and a piston rod 33. This piston rod is operatively connected to the floor sections by means of a chain 34 which passes over a pulley 35. This pulley is preferably mounted upon ball bearings so that it will rotate as easily as possible. The chain 34 passes over the pulley 35 and then to the free extremity of the foremost wall of the lifters 24, as illustrated in Fig. 5. It is obvious that if the piston 32 be moved to the right in Fig. 5 the chain 34 will be tightened and will cause the lifters to rotate to a ver-

tical position and lift the floor sections 21 and 22 upward to an inclined position, as illustrated in Fig. 4. The lifters are never raised to an absolutely vertical position but to a position nearly vertical so that when 70 the pressure of air on the piston 32 is released the lifters will fall back or return to their normal position under the weight of the floor sections.

The cylinder 31 is adapted to be connected 75 by means of a pipe 36 or 37 to air operating means carried upon the engine. Preferably this pipe 36 extends to a compressed air reservoir on the engine and means are provided on the engine whereby the compressed air 80 from this reservoir may be allowed to flow into the cylinder 31 to actuate the piston 32. It is obvious, however, that a reduction in pressure might be made in one end of the cylinder and atmospheric air be allowed to 85 cause the operation of the piston. I do not wish therefore to limit myself to any particular means whereby air pressure may be used to operate the piston 32. From the pipe 36 extends a pipe 37 whereby air pressure may be carried on back to the pipe 36 of the next wall of the train. It will be understood, of course, that these pipes 36 and 37 are provided with suitable couplings whereby they may be connected up with the 95 pipes of the next adjacent cars.

In order to provide means whereby the lifters may be operated without the necessity of using compressed air, I have attached to the forward lifter of each car a chain 38 100 which extends out through an opening 39 formed in the front wall of the car and is provided with a shackle 40 to which draft animals may be connected or to which the engine of a train may be connected, as desired. In order to secure a proper purchase upon the lifters 24 when they are in their lowered or horizontal positions I mount upon the forward end of the car and on a line beneath the floor the pulley 41. 105 The chain 38 will rest upon this pulley when the lifters are in their lowered or horizontal position and this will cause the chain to pass upward and forward from the extremity of the adjacent lifter so that the first 110 pull upon the lifters is upward as well as forward until the lifters have shifted to a position where the chain 38 is carried off from the pulley 41. The pulley 41 is not necessary for the chain 38, however, as this 115 chain passes out through the opening 39 and on a plane above the pivotal center of the lifters.

If it be desired to transform the car as illustrated in Figs. 1 and 3 into a flat car, 120 the supporting rods 11 and side walls 12 may be removed from engagement with the posts 7, the supporting rods being provided with nuts at their ends which may be removed to permit the removal of the sup- 125 130

porting rods, and then if it be desired the end walls 8 may be turned down flat upon the floor. There is thus provided a flat car having a floor but not having either ends or sides. If it is desired to provide a flat car having ends, the end members 8 are lifted in their vertical position. These members 8 are locked in their vertical position by means of bolts 42 passing through the 10 posts 7.

It will be seen that I have provided a very simple form of dumping car and one in which the contents of the car are readily dumped on each side of the track. After the 15 contents of the car have been dumped the lifting members and the floor fall back to their normal position so that the car is in the condition to receive a second load of material just as soon as the stakes are engaged 20 with the straps 17.

It is to be understood that the pipes 36 and 37 are to be uncoupled while the train is running and these pipes are only to be coupled to each other when it is desired to 25 dump the cars. It will be obvious also that valves might be provided which would permit of the dumping of certain of the cars of the train, leaving the other cars of the train undumped. The car or train of cars 30 can be controlled by an engine at either end and if the engine is not provided with means for compressing air in the cylinder 31 or if the car is placed upon a side track without an engine, it is possible to unload the car 35 either by attaching a team to the shackle 40 or by connecting the shackle to the engine itself. The team or the engine will then draw the lifting members 24 into their operative position to dump the car.

40 The stakes 14 are so arranged that they cannot be accidentally disengaged and these stakes will securely hold the sides of the car from any outward movement until they are released. After the contents of the car 45 have been dumped it is an easy matter to return the stakes to their original position.

Having thus described my invention, what I claim is:

1. In a dumping car, a floor formed of 50 two longitudinally extending sections hingedly supported for movement in a plane transverse to the length of the car, and power-operated members disposed beneath the floor and engaging therewith and adapted to be raised 55 from a horizontal to an approximately vertical position to thereby raise the sections to an outwardly and downwardly inclined position.

2. In a dumping car, a floor section hingedly supported upon the body of the car, 60 means movable in the direction of the length of the car for raising or lowering the floor section from a horizontal position to an inclined position, and draft devices connected 65 to said means and extending longitudinally

of the car whereby said means may be operated by tractive force.

3. In a dumping car, a floor formed of two longitudinally extending sections hingedly supported at their outer edges and normally disposed in a horizontal position, means disposed beneath said sections for raising or lowering the sections from a horizontal to an inclined position, end members hingedly supported upon the body of the car 75 and movable from a vertical position to a horizontal position against the floor sections, and side members hingedly and detachably supported.

4. In a dumping car, a floor formed of 80 two longitudinal sections hingedly supported upon the body of the car at their outer edges, and means for raising the free edges of said sections to thereby raise the sections to an outwardly and downwardly inclined 85 position.

5. In a dumping car, a floor formed of two longitudinal sections hingedly supported at their outer edges, members normally disposed in a horizontal position beneath 90 said floor and hinged to the body of the car, and means whereby said members may be raised from a horizontal position to an approximately vertical position to thereby raise said floor section from a horizontal position to an upwardly and laterally inclined 95 position.

6. In a dumping car, a floor formed of two longitudinally extending sections hingedly supported at their outer edges upon the 100 body of the car and a plurality of lifting members hinged to the body of the car and normally disposed in a horizontal position, said members being approximately triangular in form, and means whereby said members 105 may be raised from a horizontal position to an approximately vertical position to thereby lift the floor sections from a horizontal position to an angular position.

7. In a dumping car, a floor formed of 110 two longitudinally extending sections hingedly supported at their outer edges upon the body of the car and a plurality of lifting members hinged to the body of the car and normally disposed in a horizontal position, 115 said members being approximately triangular in form, and means whereby said members may be simultaneously raised from a horizontal position to thereby lift the floor sections from a horizontal position to an 120 angular position.

8. In a dumping car, a floor formed of two longitudinally extending sections hinged at their outer edges to the body of the car, 125 said sections being normally horizontal and a plurality of lifting members hinged to the body of the car and disposed beneath the floor, the pivotal axis of each member extending transversely of the car, means for raising said members from a horizontal to 130

an approximately vertical position, and rollers mounted upon the side edges of said members and adapted to engage with the floor section as the members are raised.

5 9. In a dumping car, a floor formed of two longitudinal sections hingedly supported at their outer edges, the sections normally lying in a horizontal plane, and a plurality of triangular lifting members disposed beneath the floor and hinged each at its base to the car body for movement in a plane parallel to the longitudinal axis of the car, the side edges of said members being cut away, rollers mounted in said cut-away portions of the side edges and adapted to engage with said floor sections, means connecting all of said lifting members to each other for simultaneous movement, and means for raising said members from a horizontal to an approximately vertical position to thereby lift the floor sections to an inclined position.

10 10. In a dumping car, a floor formed of two longitudinal sections hingedly supported at their outer edges, sides longitudinally supported upon the car body and normally depending in a vertical position above the floor sections, means for locking said sides in a vertical position but when shifted permitting the sides to turn outward, lifting members disposed beneath the floor and adapted to be raised to an approximately vertical position to thereby raise the floor sections to an outwardly and downwardly divergent position to discharge material beneath said sides, and means for raising or lowering said members.

11 11. In a dumping car, a body having posts at the corners, a floor formed of two longitudinal sections hingedly supported at their outer edges upon said body but normally lying in a horizontal plane, a plurality of lifting members hingedly attached to the floor of the car and movable from a horizontal position to a vertical position, means for raising or lowering said lifting members, rods supported by the posts on each side of the car, side members hingedly mounted upon said rods and depending normally in a vertical plane, and means for locking said side members in their vertical position or unlocking the side members to permit them to be turned outward on their hinges by the pressure of material within the car.

12 12. In a car, a body, two longitudinally extending floor sections hingedly supported at their outer edges upon the car body and normally disposed in a horizontal plane, a plurality of triangular lifting members disposed beneath the floor and each having trunnions passing through the side beams of the car body, anti-friction bearings in which said trunnions are disposed, detachable caps closing said anti-friction bearings,

and means for simultaneously lifting said lifting members from their horizontal position to an approximately vertical position to thereby engage the floor sections and rotate them into an outwardly and downwardly diverging relation.

13 13. In a dumping car, a floor formed of two longitudinal sections hingedly supported at their outer edges and normally disposed in a horizontal plane, lifting members disposed beneath the floor hinged to the car body and adapted to be raised to an approximately vertical position to thereby raise the floor sections to an outwardly and downwardly inclined position, pressure operated means for lifting said members, and a flexible connection attached to said members and passing out through the end of the car whereby said members may be raised by tractive force.

14 14. In a dumping car, a floor formed of two longitudinal sections hingedly supported upon the body of the car at their outer edges, lifting members each hinged to the car body normally disposed in a horizontal plane but movable into an approximately vertical plane to thereby lift the floor sections into inclined positions, an air cylinder mounted upon the body of the car, a piston operating therein, a flexible connection extending from said piston and operatively connected to all of the floor sections, means whereby air pressure may be exerted upon said piston to cause it thereby to raise the lifting members, and a flexible connection attached to said lifting members and passing out through the end of the car whereby tractive force may be applied to said lifting members to raise them.

15 15. In a car, a body, side walls, stakes mounted upon the side walls for longitudinal and rotative movement, a socket on the body with which the lower ends of said stakes engage, and members on the side walls with which the stakes engage when in a vertical position but permitting the stakes to be lifted and rotated.

16 16. In a car, a body, a side wall, stakes mounted upon the side wall for longitudinal and rotative movement, sockets on the body with which the ends of the stakes engage when the stakes are lowered, L-shaped supporting members mounted upon the side wall with which the stakes engage when in a vertical position, said members permitting the elevation and rotation of the stakes and supporting members on the side wall with which the stakes engage when they are lifted from engagement with the sockets on the body and rotated into an approximately horizontal position.

17 17. In a dumping car, a car body, posts disposed at the corners of the car body, sills extending longitudinally of the car body and forming part thereof, rods ex-

tending longitudinally of the sills and engaging with said posts, a floor formed in two longitudinal sections each hingedly connected to one of said rods, the sections normally lying in a horizontal plane, a plurality of triangular lifting members disposed beneath the floor and having trunnions passing through the said sills, said lifting members being normally in a horizontal plane but adapted to be raised to an approximately vertical plane to thereby raise the floor sections to inclined positions, rods connecting the upper ends of the posts, side members hingedly mounted upon said rods and extending longitudinally of the car above the sills, means mounted upon the side members for operatively engaging the sills to hold the side members in a vertical position but disengageable from the sills

to permit the side members to swing outward, pressure operated means for raising or lowering the lifting members, and tractor operated means for raising or lowering the lifting members.

18. In a dumping car, a floor formed of two longitudinal sections hingedly supported at their outer edges, and members disposed beneath the floor and adapted to be raised to an approximately vertical position to thereby raise the sections to an outwardly and downwardly inclined position.

19. In testimony whereof I hereunto affix my signature in the presence of two witnesses.

CHARLES DUNNING.
